COPY-MAKING APPARATUS

Bruce R. Hannah, Staten Island, N.Y., and Francis G. La Morte, West Orange, and Frank L. Kratcoski, Dover, N.J., assignors to Dynagraphic Systems, Inc., Cedar Knolls, N.J., a corporation of Delaware

Continuation-in-part of design application Ser. No. 12,772, July 15, 1968. This application Apr. 2, 1969, Ser. No. 16,559

Term of patent 14 years

Int. Cl. D16—05

U.S. Cl. D61—1

Fig. 1

Fig. 2

Fig. 3

Fig. 4

FIG. 1 is a view in perspective of the front, top and one side of the "copy-making apparatus" embodying our new design;

FIG. 2 is a side elevational view of the side opposite that shown in FIG. 1;

FIG. 3 is a rear elevational view thereof; and

FIG. 4 is a top plan view thereof.

This application is a continuation-in-part of design patent application Ser. No. 12,722, filed July 15, 1968, now abandoned.

We claim:

The ornamental design for copy-making apparatus, substantially as shown and described.
